ADJUSTABLE GARMENT HANGERS

John Ambrosino, Flushing, N. Y.

Application September 14, 1954, Serial No. 455,867

3 Claims. (Cl. 223—88)

This invention relates to garment hangers, and more particularly to a garment hanger having adjustable skirt or trouser supporting members.

The invention provides a simple and inexpensive hanger which holds a garment from within the waistband in its natural form without any spring pressure as in so-called scissor type garment hangers which sometimes unduly stretch and deform a garment.

The garment hanger of this invention is positively slip-proof, a feature which is particularly important when the garment is to be stored in an overcrowded closet or store rack.

The invention consists in the combination of any standard coat hanger with a pair of suitably shaped members which depend from the hanger, are longitudinally slidably mounted thereon, and are provided with outwardly facing projections to engage a garment, such as a skirt or a pair of trousers below the waistline and firmly support the same against any but intentional pressure thereagainst to remove the garment.

The invention will be further described hereinafter, several preferred embodiments thereof shown in the accompanying drawing wherein like characters of reference indicate similar elements, and the invention will be finally pointed out in the appended claims.

In the drawing,

Fig. 1 is a view of the preferred form of my garment hanger showing two skirt supporting members frictionally engaging the coat supporting members, and in dot-dash lines the hanger upon folding thereof for convenient storage;

Fig. 2 is an enlarged perspective view, partly in section, of one skirt supporting member;

Fig. 3 is a section taken on line 3—3 in Fig. 1;

Fig. 4 shows one portion of a slightly different garment hanger wherein the skirt supporting members are movable along a horizontal carrier connecting the outer ends of the coat supporting members;

Fig. 5 is an enlarged, partly sectional perspective view of the skirt supporting member shown in Fig. 4;

Fig. 6 shows a modification of the garment hanger illustrated in Fig. 4;

Fig. 7 shows still another embodiment of my invention wherein a hanger for skirts only is shown;

Fig. 8 is an enlarged vertical section taken on line 8—8 in Fig. 7; and

Fig. 9 is an enlarged view of one portion of the hanger shown in Fig. 1, wherein the locking action between the skirt supporting and the coat supporting member is shown in more detail.

Referring now to the illustrated embodiments, and more particularly to Fig. 1, there is shown a hanger 10 having two suitably rounded and somewhat downwardly inclined coat supports 11 and 12, and a hook 13. As shown in dot-dash lines, supports 11 and 12 may be pivotally joined and the entire hanger, when not in use, collapsed upwardly whereby supports 11, 12 assume the dot-dash positions 11', 12'. This mode of collapsing

2

the hanger offers various advantages over the folding methods used, for example, in scissor-type hangers wherein the hanger is collapsed downwardly, i. e. to leave the hook 13 exposed upon folding. The upwardly folded hanger (a) requires less space for storage, and (b) does not require a special lock to retain the supports 11, 12 in desired position to suspend a coat thereon.

Longitudinal grooves 14, 15 are cut into vertical walls on both sides of members 11, 12, and terminate toward the center of the hanger. The lower ends of grooves 14, 15 are free to receive skirt supporting members 16, 17, one of which is shown enlarged in Fig. 2. A skirt 20 is shown in section, having a waistband 21 and a lower enlarged portion 22 held by preferably rounded outwardly projecting portions 18, 19 of members 16, 17, respectively.

The upper, retaining, portion 23 of member 16, shown in Fig. 2, consists of a bottom wall 24 and two vertical walls 25, 26 having inwardly bent flanges 27, 28 slidable in slots or grooves 14, 15 of members 11, 12. This retaining portion 23 of member 16 receives a suitably shaped flat spring 29 which frictionally engages the lower side of member 11, as shown in connection with members 12 and 17 in Fig. 3, and prevents sliding of member 16 save when sufficient pressure is exerted thereagainst by the user of the garment hanger. When a skirt is supported by the members 16, 17, the weight of the skirt acts inwardly against the lowermost portions 18, 19 of said members, in the direction of arrow A as shown in Fig. 9, and instead of sliding in the grooves 14, 15, members 16, 17 tend to pivot around the contacting surface of spring 29, whereby corner a abuts against the lower wall or channel or groove 14, and corner b abuts against the bottom wall of member 11, thereby preventing any movement of member 16. This position of member 16 is shown somewhat exaggerated for better illustration in dotted lines in Fig. 9, under 16'. As shown in Fig. 3, grooves 15 are of a width just sufficient to permit insertion of flanges 27, 28 of member 17 therein, and no actual pivoting takes place. However, when it is desired to displace the member 16 to either remove the skirt therefrom or to suspend a garment thereon, the force B closely below member 11 is applied thereagainst and the member 16 will readily move in either direction, e. g. in the position shown in dot-dash lines in Fig. 9, under 16".

As seen in Figs. 2 and 3, the vertical walls 25, 26 of the upper portions of members 16, 17 are preferably bent outwardly to provide two vertical flanges 31, 32 which serve as abutments for the fingers of the user, to facilitate the movement of members 16, 17 in either direction.

Fig. 4 shows a slightly different hanger comprising a horizontal bar 130 having notches or teeth 131 preferably along its entire length. A somewhat different skirt supporting member 116 is shown in Fig. 5, with one vertical wall 126 partly broken away to show the mode of insertion of a spring 129 which is suitably shaped so as to act as a pawl in cooperation with the teeth 131 on bar 130. To adjust member 116, the lower end 129a of spring 129 is pressed downwardly to disengage the spring from teeth 131 and the member 116 is then moved to right, whereas the movement to left does not require the withdrawal of spring 129 since the spring will merely ride on the teeth when the member 116 is pushed outwardly.

65 A modification of this hanger 110 is shown in Fig. 6. Here, a horizontal bar 130 is shown without notches and the member 116 has a spring 129 equal in shape to that shown in Fig. 2.

Finally, Fig. 7 shows a further simplification, wherein the hanger is intended for skirts or trousers only and the member 216 completely surrounds the bar 230 providing a pusher 231 to adjust the member 216 in desired posi-

tion. Because of the provision of pusher 231, outwardly facing flanges 31, 32 shown in Figs. 2 and 3 may be omitted in this member 216.

Aside of its stability, reliability and adjustability, the novel hanger, due to the simplicity of its construction, has obvious advantages for mass production over scissor-type hangers whose production costs are incomparably higher. As the forces acting at the lower ends of the skirt supporting members shown in Figs. 1, 6 and 7 tend to automatically lock the structure, the hanger will not release a garment even in an overcrowded closet and will lock more securely in direct proportion to the increase of the applied force. It will unlock and permit the sliding of the skirt supporting members only when the user applies a force in a direction parallel to the hanger portion supporting the skirt supporting members, i. e. either the jacket supporting members or one of the horizontal carriers, whereby only the relatively weak frictional force between the spring and the jacket supporting member or bar is to be overcome, or the spring 129 must be disengaged as shown in Fig. 4.

Obviously, the grooves 14, 15 may be omitted in Fig. 1 and the upper portions 23 of members 16, 17 made to completely surround the members 11, 12, or the upper portions 23 may be held in a single groove in members 11, 12. Also, provided the material of member 16 has sufficient inherent resiliency, spring 29 may be omitted and the bottom wall of member 16 slotted and stamped to frictionally engage member 11.

When in use, the two skirt supporting members are slid inwardly toward the hook and then inserted into the skirt so that their lower portions engage the garment below the waistband. The two members are then moved outwardly until they firmly engage the garment. Members 16, 17 should be arranged substantially symmetrically with respect to hook 13 to maintain the garment carrying hanger in equilibrium. To remove the skirt and to then again suspend the garment, only one skirt supporting member must be moved, first inwardly and then outwardly, the other member need not change its position any more.

While it is believed that the above detailed description will guide persons skilled in the art to practice my invention, I do not desire to be limited to the exact details illustrated in the drawings, but only by the scope of the appended claims.

I claim:

1. The combination of a garment hanger having a hook and an elongated carrier element with a pair of skirt supporting members attached in mirror reverse to said carrier element, said hook extending above the median portion of said carrier element, said carrier element

having two longitudinal ends and at least a part thereof being of uniform cross-sectional area from said ends toward the median portion thereof, each of said skirt supporting members having a retaining portion of a configuration complementary to the configuration of said part of said carrier element and including spaced, substantially parallel, generally flat surfaces slidably guided along cooperating surfaces on the carrier element for restricting same to longitudinal movement along said part of said carrier element from said ends toward said median portion thereof, a resilient element attached to each of said retaining portions and in permanent frictional engagement with said carrier element for maintaining said skirt supporting members in a state of immobility when no external force in the longitudinal direction and applied in the close proximity of said part of said carrier element is exerted on said retaining portions, each of said skirt supporting members further including a downwardly extending leg, the upper extremities of said legs being integral with said retaining portions and the lower extremities of said legs having means for engaging and retaining a garment below the waistline thereof.

2. The structure of claim 1, wherein said garment hanger further includes a coat supporting member and said hook is attached to the median portion thereof, said carrier element being a bar with said ends thereof attached to the free extremities of said coat supporting member.

3. The combination of claim 1, wherein said carrier element is an elongated horizontal bar with said hook attached to the median portion and extending above said bar, said retaining portion of each of said skirt supporting members being a tubular body for receiving said bar and slidably therealong between said hook and the respective ends of said bar, each of said retaining portions having a projecting handgrip member for moving said skirt supporting members along said bar.
